Clarke & Carpenter
ATTORNEYS

UNITED STATES PATENT OFFICE.

JOHN M. YOUNG, OF BROOKLYN, NEW YORK, ASSIGNOR TO AMERICAN CAN COMPANY,
OF NEW YORK, N. Y., A CORPORATION OF NEW JERSEY.

CONTAINER.

Application filed December 4, 1924. Serial No. 753,763.

My present invention relates to tearing strip cans and has for its main object the provision of a practical and inexpensive hinge construction whereby the upper portion of the container may be used in conjunction with an interior collar to provide a hinged cover for use after the tearing strip has been removed.

The invention is, perhaps, particularly adapted to tobacco cans of the flattened or pocket shape, in which a combined hermetic and hinge cover arrangement is especially desirable since the ordinary hinge cover, though very convenient for use while the contents are being consumed, does not afford sufficient protection against drying out of the tobacco during storage and shipment of the cans. In accordance with the invention, the can, when packed, is hermetically closed and when received by the customer, is adapted to be opened by removal of the tearing strip, whereupon the upper portion of the container becomes usable as a hinge cover by reason of the construction provided by the invention.

Numerous other objects and advantages of the invention will be apparent as it is better understood from the following description, which, taken in connection with the accompanying drawings, discloses a preferred embodiment thereof.

Referring to the drawings,

Figure 1 is a perspective view of a tobacco can in which my invention is embodied;

Fig. 2 is a partial perspective view thereof with the tearing strip removed and the interior collar broken away for better illustration; and

Fig. 3 is an enlarged sectional view, taken substantially upon the section line 3—3 in Fig. 1.

Upon said drawings, I have shown, for illustrative purposes only, a preferred form of my invention, in which the reference character 11 indicates a container body closed by means of the usual vertical seam 12 and having a bottom end 13 and a top 14, which latter is permanently secured in place by means of a seam 15. Said body is scored circumferentially, as shown at 16 and 17, setting off a tearing strip 18 which is provided with a protruding tongue 19 adapted to be engaged by a key for removal of the strip to open the container. Arranged within the container and extending across the tearing strip 18 is a collar member 21, which is pref-

erably curled at the top, as indicated at 22, and is adapted to cooperate with the portion of the container above the upper score line 17 when the latter is converted into a hinge cover, in manner which will now be described.

A hinge member, comprising a strip 23 of flexible material, such as thin gage brass, is disposed on the interior of the container between the collar 21 and the body 11, and is secured to said body, preferably by spot welding, at points 24 and 25, disposed respectively beneath and above the scored area, or tearing strip 18. As will be apparent from an inspection of Fig. 2, said strip 23, thus disposed and secured within the body, provides a hinge connection between the body of the can and a flange 26 on the cover, which is provided by removal of the tearing strip. The parts used and the manufacturing operations required are simple and inexpensive and the hinge is highly efficient in action.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A can, comprising a body provided with score lines setting off an encircling tearing strip beneath the top, the body being in one piece with said tearing strip, a collar member arranged within the body and extending across the tearing strip, and a flexible hinge strip secured to the body beneath and above said tearing strip.

2. A can, comprising a body provided with score lines setting off an encircling tearing strip beneath the top, the body being in one piece with said tearing strip, a collar member arranged within the body and extending across the tearing strip, and a flexible hinge member disposed between the collar and body and secured to the latter beneath and above said tearing strip.

3. A can, comprising a body provided with score lines setting off an encircling tearing strip beneath the top, the body being in one piece with said tearing strip, a collar member arranged within the body and extending across the tearing strip, and a hinge strip,

of flexible brass secured to the body beneath and above said tearing strip.

4. An hermetically sealed can having lines of severance extending about the body setting off a tearing strip portion, the body being in one piece with said tearing strip, and a separate strip of flexible material secured to said body above and below said lines of severance whereby to provide a hinge cover from the part of said can above the tearing strip portion when said tearing strip portion is removed.
5. An hermetically sealed can having lines of severance extending about the body setting off a tearing strip portion, the body being in one piece with said tearing strip, and a sep-

arate strip of flexible brass secured to said body above and below said lines of severance whereby to provide a hinge cover from the part of said can above the tearing strip portion when said tearing strip portion is removed. 20

6. A cover for a vacuum sealed container hingedly united to the main body of the container by a separate flat one piece member of flexible material functioning as a hinge, and a collar over which said cover opens and closes as the hinge is flexed, said cover formed from the main body part by severing said part about the collar. 25

JOHN M. YOUNG.
